UNITED STATES PATENT OFFICE.

JOHN F. BRAND, OF UTICA, NEW YORK.

BOTTLE-LABEL.

1,159,164.

Specification of Letters Patent. Patented Nov. 2, 1915.

Application filed March 12, 1915. Serial No. 13,922.

To all whom it may concern:

Be it known that I, JOHN F. BRAND, a citizen of the United States, residing at Utica, in the county of Oneida and State of New York, have invented new and useful Improvements in Bottle-Labels, of which the following is a specification.

The invention relates to labels, and more particularly to the class of bottle labels.

10 The primary object of the invention is the provision of a bottle label wherein a name plate will be displayed upon the body of the bottle, thereby indicating the user or owner of the same, thus making it impossible for 15 the surreptitious use thereof without instant detection.

Another object of the invention is the provision of a bottle label of this character wherein the name plate bearing the indicia 20 indicative of the user or owner of the bottle is locked so as to prevent the possibility of the removal thereof without damage to or the breaking of the bottle.

A further object of the invention is the 25 provision of a bottle label of this character which is simple in construction, reliable and efficient in its purpose, and inexpensive in manufacture.

With these and other objects in view, the 30 invention consists in the construction, combination and arrangement of parts as will be hereinafter fully described, illustrated in the accompanying drawing, and pointed out in the claim hereunto appended.

35 In the drawing:—Figure 1 is a fragmentary side elevation of a bottle with the label constructed in accordance with the invention applied. Fig. 2 is a vertical sectional view. Fig. 3 is a sectional view on 40 the line 3—3 of Fig. 1.

Similar reference characters indicate corresponding parts throughout the several views in the drawing.

Referring to the drawing in detail, A designates a portion of the body of a bottle, which in this instance is the representation 45 of a milk bottle of the ordinary well-known construction, although the bottle may be of any other style or type, and has thereon the 50 label device hereinafter fully described.

The label device comprises a base plate 5,

which is shown of rectangular shape, although it may be of any other desirable shape, having formed at both longitudinal edges and one end edge outwardly and inwardly bent flanges 6 to provide cleats or guides having a name plate 7 which is slidably engaged therein. This name plate 7 is preferably made from metal and has stamped, printed or otherwise marked thereon indicia serving as identification, such as the name and address of a person, to designate the ownership or user of the bottle.

The base plate 5 is formed on its rear face at opposite ends with anchoring ribs 8 so that the plates can be molded in the wall of the body A of the bottle to become a permanent part thereof, and to remove it the body A will necessarily have to be broken or damaged to a degree for rendering it unfit for use.

Cut from the base plate 5 near the ends thereof are resilient tongues or wings 9 which are outwardly bent at an angle to the plane of the outer face of the plate and serve to frictionally bind and secure the name plate 7 upon the base plate 5 so as to hold it locked thereto.

Formed on the inner face of the name plate 7 are cam face stops 10, which, on the 80 sliding of the said plate in the guides or flanges 6, will ride over the tongues or wings 9 for the positive locking engagement of the latter with the stops 9 to fasten the name plate 7 in position, thereby making it impossible to remove the same.

From the foregoing it is thought that the construction, manner of application, and the use of the invention will be clearly understood, and therefore a more extended explanation has been omitted. However, it is to be implied that changes variations and modifications may be made as will come properly within the scope of the appended claim without departing from the spirit of 95 the invention or sacrificing any of its advantages.

What is claimed is:—

A label structure comprising a base plate provided with guide flanges at opposite longitudinal edges and at one end edge, resilient tongues cut and bent slightly outwardly 100

from the base plate and disposed in spaced relation to each other at two points thereof, and a name plate slidably engaged in the flanges, and cam faced shoulders on the inner side of the name plate and slidable over the tongues for the automatic locking engagement of the latter with the shoulders.

In testimony whereof I affix my signature in presence of two witnesses.

JOHN F. BRAND.
